Continuation-in-part of application Ser. No. 523,408, Jan. 27, 1966. This application June 23, 1966, Ser. No. 559,804

6 Claims. (Cl. 166—38)

ABSTRACT OF THE DISCLOSURE

An annulus around a well in an oil stratum is burned out to improve its permeability and subsequent oil production by installing a permeable tubular ceramic liner downhole, injecting a slug of autoignitable fuel, such as tung oil, thru the liner into the oil stratum, injecting a following slug of liquid hydrocarbon miscible with said fuel to free the liner of said fuel, driving the aforesaid slugs deeper into the stratum with injected inert gas, and thereafter injecting air thru the well into the stratum to contact, ignite, and burn out the injected fuel and in-place carbonaceous material.

This application is a continuation-in-part of our co-pending application S.N. 523,408, filed Jan. 27, 1966, which is a continuation-in-part of our co-pending application S.N. 451,652, filed Apr. 28, 1965 now abandoned.

This invention relates to a process for igniting an oil-bearing subterranean stratum for propagating the resulting combustion zone thru the stratum to produce oil therefrom, to an autoignitable fuel composition therefor, and to a method of opening up a stratum around a well to increased flow.

The production of oil from an oil-bearing stratum by in situ combustion is an accepted process in the petroleum industry. In order to propagate a combustion zone thru a stratum, it is necessary to ignite the in-place oil in a selected area of the stratum prior to the actual driving step of the process. Common techniques for igniting the oil in a stratum comprise burning a fuel pack such as oil-soaked charcoal in a well penetrating the stratum, heating the stratum around the ignition well with a gas-fired heater or an electric heater, heating the stratum with a thermite starter, or with rocket fuels, etc.

A more recent method is that disclosed in U.S. Patent 2,683,510 (Dec. 9, 1958) wherein a fuel spontaneously ignitable in contact with a gaseous oxidant is burned in the ignition well by depositing the fuel therein and contacting same with the gaseous oxidant whereby the fuel ignites and raises the temperature of the crude oil in the stratum adjacent the well to ignition temperature. Continued injection of air into the ignited area moves the combustion zone thru the stratum toward a production well so as to produce oil therein.

In some in situ combustion operations, a permeable ceramic liner is utilized in the ignition well which may thereafter become an injection well or a production well. Such a liner is disclosed and claimed in the co-pending application of G. B. Heckler and R. F. Meldau, S.N. 510,249, filed Nov. 29, 1965. When utilizing a permeable

2

ceramic liner of this nature and an autoignitable fuel, the liner absorbs fuel which in some instances is polymerizable in place during subsequent heating, resulting in plugging of the ceramic liner and obstruction of the flow of fluids into and/or out of the stratum.

In all of the foregoing ignition methods, for heat to flow into the stratum adjacent the ignition well at a desirably high rate, it is necessary for the heat source to operate at a very high temperature. In some cases these high temperatures severely damage the formation around the ignition well. When the well casing extends thru the oil-bearing stratum, the casing can also be severely damaged. These high temperatures can even damage other parts of the well-completion apparatus.

This invention is concerned with an autoignitable fuel composition for use in a method or process for igniting an oil-bearing stratum around an ignition well without overheating the wall of the wellbore and any downhole equipment within the oil-bearing stratum or in burning out solid to semi-solid carbonaceous deposits around a wellbore.

Accordingly, it is an object of the invention to provide an autoignitable fuel composition for igniting an oil-bearing stratum around an ignition well which avoids overheating of the wall of the wellbore and equipment therein. Another object is to provide a method or process for igniting an oil-bearing stratum around a well therein to establish in situ combustion in the stratum, which prevents overheating and damage to the wall of the wellbore and equipment therein. A further object is to provide a method of initiating in situ combustion in an oil-bearing stratum for propagating the resulting combustion zone thru the stratum between wells therein to produce oil thru one of said wells. Another object is to prevent polymerization of certain autoignitable fuels in a ceramic liner in an ignition well when using such fuels. Other objects of the invention will become apparent to one skilled in the art upon consideration of the accompanying disclosure.

A broad aspect of the process of the invention comprises depositing a liquid fuel in an oil-bearing stratum around a well penetrating same, said fuel being spontaneously ignitable or autoignitable in contact with a gaseous oxidant, driving the fuel into the stratum so that the leading edge of the deposited injected fuel is spaced substantially from the wall of the wellbore, and subsequently injecting a gaseous oxidant thru said well or thru an offset well so as to force the oxidant into contact with the spontaneously ignitable fuel and ignite same in an area of the stratum spaced from the wall of the ignition well, also igniting the in-place crude oil. In this manner, the method or process develops a zone of elevated temperature within the oil-bearing stratum around the wellbore but spaced therefrom sufficiently to provide an insulating annulus between the hot combustion zone and the wall of the wellbore. This technique avoids overheating down-hole equipment and allows the well to be completed for best sand control where sand production is a problem, as in unconsolidated oil sands. Likewise, overheating of the sand in the combustion zone is avoided because of the relatively low ignition point of the spontaneously ignitable fuel and the ignition of the native crude oil at its kindling temperature. This technique also assures that after the ignition temperature has been achieved there

remains enough fuel for the propagation of a counterflow combustion front into the stratum by injection of air or other O₂-containing gas thru the offset well(s).

One procedure for igniting the in-place fuel involves injecting air thru one or more offset wells so as to ignite the leading edge of the fuel mass and cause the resulting combustion zone to move countercurrently to air flow toward the offset well(s) (reverse burning front). The other procedure comprises injecting air thru the well thru which the fuel was injected to establish a direct drive of the combustion zone. It is to be understood that the term "air" is illustrative of other O₂-containing, combustion-supporting gases.

In one embodiment of the invention, injection of a slug of the autoignitable fuel is followed by injection of a second slug of a hydrocarbon oil of substantially higher ignition point than the fuel to drive the autoignitable fuel into the stratum away from the wall of the ignition well. The liquid hydrocarbon thus injected should be miscible with the fuel so as to flush the fuel from a narrow annulus of the stratum adjacent the wellbore. In the event a ceramic liner is utilized in the ignition well, this feature of the invention is particularly advantageous in freeing the porous liner of autoignitable fuel, thereby decreasing the heating within the ignition borehole and preventing polymerization of the fuel in the liner (in the event the fuel is polymerizable).

Hydrocarbon oils suitable for use as the second slug include liquid hydrocarbons ranging from gasoline to light crude oil and including diesel oil, kerosene, gas oil, etc. The liquid hydrocarbon to be injected following the fuel slug should be miscible with the fuel and have an A.S.T.M. final boiling point less than 700° F. with a carbon residue less than 1.0 percent by weight. After injection of the slug of liquid hydrocarbon thru the ignition well into the surrounding stratum, it is preferable to inject a slug of non-oxidizing gas to drive the fuel and liquid hydrocarbon into the stratum away from the ignition well a short distance, such as one foot to several feet. However, this step may be omitted and oxidant, such as air or other O₂-containing, combustion-supporting gas, may be injected directly behind the slug of hydrocarbon liquid which is not autoignitable. This assures ignition of the autoignitable fuel in an annulus spaced from the ignition well.

After ignition of the autoignitable fuel, the injection of oxidant (air) is continued so as to move a combustion zone away from the wellbore toward one or more offset wells to become production wells. It is also feasible to either reverse the flow of air after ignition, or inject air thru the offset well(s) so as to move the resulting combustion front toward the offset well(s) countercurrently to the flow of air thru the stratum.

Another embodiment of the invention comprises forming an intimate mixture of the autoignitable fuel, the higher ignition point hydrocarbon fuel and an oxidation catalyst and injecting the mixture into the area of the stratum to be ignited. Thereafter, the fuel composition is then contacted with injected O₂ (air) to ignite same.

The autoignitable fuel composition of the invention consists essentially of an intimate mixture of (1) an autoignitable fuel of the group tung oil, linseed oil (boiled or raw), red oil, castor oil, turpentine, tall oil, tall oil fatty acids, oleic acid, and linseed oil fatty acids and mixtures thereof in an amount in the range of 35 to 95 weight percent of the composition, (2) a liquid oxidation catalyst or accelerator in a concentration in the range of 0.025 to 1.0 weight percent of the fuel of (1), and (3) a liquid hydrocarbon fuel having an ignition temperature substantially above the ignition temperature of the fuel of (1), said hydrocarbon fuel ranging from gasoline to heavy crude oil. The amount of the autoignitable fuel of (1) required increases with the lighter hydrocarbon fuels of (3), at least about 35 weight percent being sufficient with crude oils and at least 75 weight percent being required with gasoline.

Another embodiment of the invention comprises burning out an annulus of carbonaceous stratum around either an injection or a production well to increase the permeability thereof and open up same to permit faster injection and production rates. The autoignitable fuel or fuel composition is deposited in an annulus of about 1 to 5 feet or more in radius immediately surrounding the well and burning thereof is effected by contact with injected O₂ and injection is continued to burn out the fuel and carbonaceous deposit, thereby greatly increasing the permeability of the annulus. The termination of O₂ injection then extinguishes the fire and injection of fluids there thru or the production of fluid hydrocarbons can be effected at faster rates. This aspect of the invention is excellent for well stimulation to increase production.

It has been demonstrated that 33 standard cubic feet of air per pound of tung oil in place in a sand is required to burn the tung oil. An Ottawa sand pack 26 inches long in a 2-inch combustion tube was saturated with tung oil. Air at 500 p.s.i. pressure was passed thru the tube at a flux of 150 s.c.f./hr.-ft.² and the tung oil was ignited and consumed.

Another test was made to determine if tung oil, when admixed with reservoir oil, is subject to autoignition. This test was performed in an isothermal 2-inch Pyrex combustion tube using an Ottawa sand pack containing 9 weight percent of a mixture of 75 percent catalyzed tung oil and 25 percent Morichal Group I crude oil (cobalt naphthenate catalyst). Air was injected into the tube at an air flux of 50 s.c.f./hr.-ft.² and the temperature reached 400° F. in 2.3 hours, the initial temperature being 140° F., simulating reservoir conditions. The pressure was 500 p.s.i. This test demonstrates the feasibility of utilizing a mixture of autoignitable fuel and crude oil as a fuel in the instant process. It also demonstrates that an autoignitable fuel, when admixed with in-place crude oil, will still function in the manner required.

In operation of the process, the injected slug of spontaneously ignitable fuel is driven into the stratum so that the leading edge thereof is at least one foot, preferably several feet, and up to 50 feet from the wall of the wellbore before contacting with the gaseous oxidant. In one embodiment of the invention, a non-oxidizing gas is injected thru the ignition well subsequent to the injection of the readily oxidizable fuel so as to drive the fuel into the stratum remote from the wellbore and render the stratum gas permeable. Any non-oxidizing gas such as oil field gas (natural gas), light gaseous hydrocarbons, combustion gas, nitrogen, etc., may be used for this purpose but oil field gas is preferred because of its ready availability and low cost.

In igniting an oil-bearing stratum containing a crude oil of high kindling or ignition point such as one of about 375° or 400° F., it is preferred to inject in admixture with the spontaneously combustible fuel a second fuel having a kindling or ignition point substantially lower than the ignition point of the native crude oil but substantially higher than the ignition point of the spontaneously combustible fuel. The less readily oxidizable fuel is incorporated in the injected slug in a concentration in the range of about 1 to 50 volume percent, the readily oxidizable fuel being in the range of 99 to 50 volume percent of the injected slug. The second fuel of higher ignition temperature comprises any liquid hydrocarbon material having an ignition temperature under ambient conditions in the range of about 275-350° F. Such fuels as kerosene, distillate, cycle oil, and some crude oils have ignition points in this range and are suitable for mixing with the spontaneously combustible fuel. Bellridge crude is an example of one crude oil which has an ignition point of about 300° F. and is suitable as the second fuel in the injected fuel slug. Morichal crudes also are effective in the autoignitable fuel composition. The less readily oxidizable fuel in the slug assures the presence of sufficient fuel at the leading

edge of the slug to generate the heat necessary to ignite the oil in place. It also helps to adjust the ignition temperature of all of the combustible material in the slug thru mixing.

The spontaneously ignitable component of the injected slug is selected from any of the well known materials which ignite spontaneously under oxidative conditions at the temperature prevailing in the stratum which is to be treated. Such materials include unsaturated compounds like turpentine, linseed oil, tall oil, tung oil, red oil, etc. Generally, the oxidizable liquids disclosed in U.S. Patent 2,863,510, excepting the amine compounds, are operable in the process. Hypergolic fuels generally are within the scope of the invention.

Suitable gaseous oxidants include air, oxygen, oxygen-enriched air, ozone, gaseous nitrogen oxides, and mixtures of these gases. When utilizing air without the O₂ enrichment and without an oxidation catalyst, the pressure required for spontaneous ignition is usually at least 30 p.s.i.g. or higher. Preferably substantially higher pressures are utilized because of the pressure necessary to force the air thru the permeable stratum to the leading edge of the fuel slug. The O₂-containing gas must have an oxygen partial pressure of at least 6 lbs. whether atmospheric air or oxygen-enriched air is utilized.

It has been found that incorporation of an oxidation catalyst in minor concentration in the injected fuel slug facilitates spontaneous ignition of the fuel and makes it feasible to ignite the fuel slug with ordinary air at atmospheric pressure. It is preferred to utilize the catalyst in liquid form so as to avoid plugging the stratum. A preferred catalyst is cobalt naphthenate, which is readily soluble in such fuels as those named above. Other catalysts include oil soluble salts and other compounds of the metals listed as oxidation catalysts in Berkman et al., *Catalysis*, Reinhold Publishing Corp., 330 W. 42nd St., New York, N.Y., 1940; pages 797-809.

While the ignition step can be effected in the stratum in the presence of connate water, it is preferred to air dry the stratum prior to the injection of the fuel slug when any substantial amount of connate water is present. In the presence of small concentrations of connate water the heating produced by the spontaneous ignition of the fuel slug increases the temperature in the contacting zone until the boiling point of water is reached under ambient conditions and the water in this heating zone is vaporized until the ignition zone is relatively dry. Then the temperature produced by the spontaneous heating of the fuel in contact with oxygen rises until the ignition point is reached and ignition is actually initiated so as to produce a burning zone. Drying out of the stratum intermediate the ignition and surrounding injection wells is readily accomplished by driving air or other drying gas thru the stratum between the wells. Following the step of drying out with an oxidizing gas, such as air, an inert gas is injected to displace the air from the section of stratum into which the autoignitable fuel is to be injected.

The following examples demonstrate the invention but are not to be construed as unnecessarily limiting same.

Example I

Runs were made with several spontaneously ignitable fuels under controlled conditions in a 2" diameter Pyrex tube containing a 2" long section of sand and liquid fuel in a sand to fuel ratio of 9:1. In all cases, the contained pack was preheated to 150° F. while flushing with nitrogen. In runs 1-13, inclusive, oxygen was passed into the tube at a rate of 5 s.c.f./hr.-ft.² at atmospheric pressure. In runs 14 and 15 air was passed into the tube at a rate of 20 s.c.f./hr.-ft.² at atmospheric pressure. The rise in temperature within the tube was balanced by external heating of the tube to maintain adiabatic conditions. Those runs which effected ignition at 150° F. do not necessarily demonstrate the lowest ignition temperature as this was the temperature at which air injection was

initiated. Data from the runs are presented in the table below:

TABLE

Run	Oxidizable material	Spontaneous ignition temp., ° F.
1	Pure boiled linseed oil	150
2	75% P. B. linseed oil, 25% Morichal Gp. II crude	200
3	50% P. B. linseed oil, 50% Morichal Gp. II crude	265
4	Dehydrated castor oil	185
5	Tung oil	155
6	Linseed oil fatty acids	150
7	Tall oil fatty acids	165
8	Red oil (oleic acid)	204
9	Crude tall oil	200
10	Crude tall oil + 1% catalyst ¹	174
11	Red oil + 1% catalyst ¹	180
12	Tall oil fatty acid + 1% catalyst ¹	150
13	Tall oil fatty acid + 0.5% catalyst ¹	150
14	P. B. linseed oil + catalyst ²	150
15	Tall oil fatty acid + catalyst ²	150

¹ Catalyst solution was lead naphthenate + cobalt naphthenate (9:1).

² Catalyst solution was cobalt naphthenate (0.1 wt. percent cobalt).

Example II

Similar tests to those of Example I were run with Morichal Group I and Morichal Group II crude oil in the sand. The crude oil was admixed with cobalt naphthenate in a concentration of 0.1 percent cobalt. The sand temperature was raised to 150° F. and O₂ at a flow rate of 5 s.c.f./hr.-ft.² was passed into the packed sand in the combustion tube and there was no autoignition of the crude oil. At atmospheric pressure Group II Morichal crude has an ignition temperature above 400° F. and the Group I crude has an ignition temperature above 350° F. Similar runs were made with tall oil fatty acid as the spontaneously ignitable fuel with concentration of catalyst varying from 0.025 to 0.1 weight percent and autoignition was readily achieved at a starting temperature of 150° F.

Igniting the spontaneously combustible fuel disclosed herein with air as an oxidant is aided by increasing the pressure substantially above atmospheric pressure. Using O₂-enriched air containing at least 40% O₂ enhances autoignition.

Example III

In another run, using pure O₂ instead of air, the pack in the combustion tube of Example I had a water saturation of 16% of the pore volume and an autoignitable oil saturation of 50% of the pore volume, using tall oil fatty acid and cobalt naphthenate in a concentration of 0.1 weight percent cobalt. In this run the temperature rose slowly until the water in the sand was evaporated and then much more rapidly as ignition took place. The ignition was terminated at 440° F. while the temperature was rising at 6° F. per minute.

Example IV

In testing the mechanics of the spontaneous ignition procedure, an 18-inch long, 2 1/4-inch diameter stainless steel tube was used. It was packed with a 2-inch section of Ottawa sand mixed with autoignitable oil (plus cobalt naphthenate) sandwiched between two sections of Ottawa sand containing Group II Morichal oil. Counterflow combustion was initiated in the autoignitable section by subjecting it to the flow of oxygen at a flux of 10 s.c.f./hr.-ft.². The autoignitable mix was a tall oil fatty acid containing 0.1 weight percent cobalt as cobalt naphthenate as catalyst. This oil mix was present at a concentration of 1710 BPAF and the flanking sections contained 1350 BPAF of Morichal Group II oil.

The total pack was heated to 150° F. (the reservoir temperature of the Group II Morichal sands), while it was flushed with nitrogen. The loss of the spontaneously generated heat when oxygen was injected was prevented by maintaining the temperature of the outside of the tube substantially equal to that of the interior with an electric heater. A period of 6.5 hours was required to bring the temperature of the sand to 800° F. by spontaneous heating. During this time, the combustion front moved from

the middle section containing the autoignitable oil mix into the upstream section containing Group II oil.

The above test with Morichal oil clearly demonstrates that in-place crude oil is readily ignitable by the process of the invention and that a combustion zone can be moved thru an oil sand countercurrently to the flow of oxygen-containing, combustion-supporting gas.

Example V

A run was made in the tube of the foregoing examples packed with Ottawa sand soaked with an autoignitable fuel composition consisting of 75% tung oil containing 0.1 wt. percent of Co, as cobalt naphthenate, and 25 wt. percent Group I Morichal crude oil, the pack consisting of 90 wt. percent sand and 10 wt. percent fuel. The temperature of the pack was brought to 140° F. with a stream of N_2 and air was then substituted for N_2 at a pressure of 500 p.s.i.g. There was immediate sustained reaction at 140° F. and the temperature of the pack rose from 140 to 201° F. in 130 minutes. Thereafter, the rate of temperature rise increased substantially, rising to 398° F. in 30 minutes. The run was terminated when the pack reached 398° F. at which time the temperature was increasing at the rate of 4° F. per minute.

A more complete understanding of the invention may be had by reference to the schematic drawing of which FIGURE 1 is an elevation in partial cross section thru an oil stratum penetrated by an ignition well and an offset well and FIGURE 2 is a graph showing the relationship between API gravity of the hydrocarbon fuel and the minimum autoignitable oil required.

Referring to FIGURE 1 of the drawing, an oil stratum 10 is penetrated by an ignition well 12 and an offset well 14. Well 12 is provided with a perforate injection tubing 16 and a permeable surrounding ceramic liner 18, tubing 16 being imperforate above the liner 18 and the liner 18 terminating substantially at the upper level of the oil stratum. Well 14 is provided with a tubing string 20 extending thru the wellhead.

In the stage of the process illustrated in the drawing, a slug of autoignitable fuel, such as tung oil 22, has been injected thru tubing 16, liner 18, and into the stratum. A second slug of liquid hydrocarbon such as diesel oil 24 has been injected in the same manner behind the slug of fuel, forming a mixture 26 of the fuel and diesel oil adjacent the interface of the slugs. At the stage of operation illustrated, the next step in the process comprises either injecting an oxidant such as air or a non-oxidizing gas such as nitrogen, combustion gas, etc., followed by oxidant injection.

It is also feasible to inject a non-oxidizing, non-deleterious gas thru well 12 to drive the fuel and liquid hydrocarbon deeper into the stratum and then inject air or other oxidant continuously thru tubing string 20 of well 14 so as to initiate ignition at the leading edge of fuel slug 22 and cause the resulting combustion zone to move thru the stratum toward well 14 with production passing thru well 12 and out tubing string 16, which passes thru the wellhead. Such gases include CO_2 , flue gas, N_2 , etc.

In FIGURE 2, line A represents the relationship between the minimum amount of tung oil required in hydrocarbon fuels of a range of API gravity to form a fuel composition (including added cobalt naphthenate) which is autoignitable at a temperature of about 150° F. In oil reservoirs of substantial depth temperatures are at this level and upwards so that autoignition of such a fuel is readily effected by injecting air, particularly at the pressures required for such injection.

To illustrate with FIGURE 2, Morichal Group II crude oil has an API gravity of 8° and requires at least 35 wt. percent tung oil mixed therewith and with catalyst to provide an autoignitable fuel composition at the minimum temperature of about 150° F. Naphtha requires a minimum of 65 wt. percent and gasoline, a minimum of 75 wt. percent. Of course, higher concentrations of tung oil

up to 95 wt. percent of the composition are operable and provide sufficient added fuel to be effective in igniting the native oil or carbonaceous material. Increasing the air injection pressure lowers the ignition point of the fuel composition in the presence of catalyst.

When combining a high viscosity crude or tar with tung oil, it improves the handling characteristics of the composition to incorporate therein at least 5 and up to 15 wt. percent of a low viscosity hydrocarbon fuel having a considerably higher API gravity. Thus, when using a crude of 8 API gravity admixed with tung oil, the viscosity of the composition is so high that it is desirable to blend therewith a hydrocarbon fuel ranging from a heavy gas oil to gasoline to lower the viscosity of the composition. The required concentration of tung oil increases as the gravity rises. Other autoignitable fuels behave similarly to tung oil.

The invention is particularly applicable to the initiation of combustion in an oil-bearing stratum around and spaced from an ignition well to be used in a reverse burning in situ combustion process wherein air is fed thru an offset injection well and forced to the combustion zone to propagate same thru the stratum to the injection well(s). Any suitable well pattern may be utilized in this operation. It is also feasible to ignite the stratum by the method of the invention in a section of the stratum spaced from the ignition well by injecting the oxidant thru an offset well and subsequently terminating injection thru the offset well and injecting air thru the ignition well so as to propagate the combustion zone to the original injection well by direct drive.

Certain modifications of the invention will become apparent to those skilled in the art and the illustrative details disclosed are not to be construed as imposing unnecessary limitations on the invention.

We claim:

1. A process for igniting and burning carbonaceous material in a restricted section of oil stratum adjacent but spaced from an ignition well therein in which a permeable ceramic tubular liner is positioned in said well down-hole within said stratum, which comprises the steps of:

- (1) injecting into said stratum thru said ignition well a slug of an autoignitable fuel (when contacted with O_2) in an amount sufficient to impregnate a substantial but limited section of the surrounding stratum;
- (2) injecting a liquid hydrocarbon miscible with the fuel of step (1) through said well and thru said ceramic liner to remove substantially all of said fuel from said liner, prevent formation of plugging material in said liner when oxidant of step (3) is injected therethru, and move said fuel out of a narrow section contiguous to said well;
- (3) subsequent to step (2) injecting a gaseous oxidant providing sufficient O_2 concentration to cause autoignition of the fuel of step (1) into said stratum thru said well and said liner into contact with said fuel so as to effect ignition thereof in said restricted section; and
- (4) continuing the injection of oxidant of step (3) so as to burn said carbonaceous material from said restricted section.

2. The process of claim 1 wherein said fuel includes an oxidation catalyst and said gaseous oxidant consists essentially of air.

3. The process of claim 2 wherein said liquid hydrocarbon in step (2) consists principally of diesel oil.

4. The process of claim 1 wherein the oil in said stratum has an ignition point of at least 375° F. and a liquid hydrocarbon material having an ignition point in the range of 275 to 350° F. is incorporated in the fuel of step (1) in a concentration in the range of 1 to 50 volume percent of the resulting fuel.

5. The process of claim 1 wherein a substantial slug of an inert gas is injected into said stratum thru said

well and said liner intermediate steps (2) and (3) to displace fuel of step (1) and liquid hydrocarbon of step (2) radially into said stratum away from said well.

6. The process of claim 1 wherein the autoignitable fuel of step (1) is selected from the group consisting of tung oil, linseed oil, tall oil, red oil, castor oil, oleic acid, linseed oil fatty acids, tall oil fatty acids, turpentine, and mixtures thereof and the fuel includes a minor amount of a catalyst of the group cobalt, lead, and manganese naphthenates, resinates, linoleinates, and octyloxyacetates and mixtures thereof.
